UNITED STATES PATENT OFFICE

1,989,761

FOUNTAIN PEN

Alexander O. McBean, Chicago, Ill.

Application November 1, 1933, Serial No. 696,129

8 Claims. (Cl. 120—47)

The invention relates to improvements in fountain pens and has for its primary object the provision of an improved fountain pen which is capable of economical manufacture and highly efficient in use.

Another object of the invention is the provision of an improved fountain pen having improved means provided therein for filling the same with ink and retaining said ink therein.

10 Other objects will appear hereinafter.

The invention consists in the combinations and arrangements of parts hereinafter described and claimed.

15 The invention will be best understood by reference to the accompanying drawing forming a part of this specification, and in which

Fig. 1 is a longitudinal section of a fountain pen embodying the invention;

Fig. 2 an enlarged transverse section thereof 20 taken substantially on line 2—2 of Fig. 1;

Fig. 3 a longitudinal section of a modified form 25 of construction; and

Fig. 4 an enlarged transverse section taken substantially on line 4—4 of Fig. 3.

25 The embodiment of the invention illustrated in Figs. 1 and 2 comprises a barrel 10, preferably made of any of the usual non-metallic materials employed for the purpose, and having the usual ink chamber therein. At one end the barrel 10 is 30 equipped with the usual pen point 11 in open communication with the ink chamber of the barrel.

The other end of the barrel 10 is closed by means of a head 12, preferably of the same material as the barrel 10, and threaded therein as 35 shown. The head 12 is provided with a piston chamber 13 fitting snugly into the ink chamber of the barrel and provided at its inner or bottom end with a closure or bottom plug 14 having a minute perforation 15 extending therethrough. The 40 piston chamber 13 is lined with a thin metallic tube or sleeve 16 of acid resisting metal, thereby providing a smooth and uniform inner surface for the piston chamber 13 which will not materially distort under ordinary conditions of use.

45 The head 12 is also provided with a protruding extension 17 having an open-ended socket 18 therein. The piston 19 operates freely in the piston chamber 13 and is provided with a piston rod 20 extending through the socket 18 and equipped 50 at its outer or upper end with an enlarged plunger head 21 snugly fitting and operating in the socket

18. A compression spring 22 is imprisoned in the socket 18 as shown. The extension 17 and plunger 21 are enclosed and protected by means of a cap 55 23 threaded at 24 on the head 12. Additional

threads 25 are also provided on the barrel 10 for the reception of an outer cap used for the protecting of the pen point 11 (not shown).

As shown, the piston chamber 13 extends into the ink chamber of the barrel 10 about half-way of the length thereof, the bottom 14 of the piston chamber thus constituting a partition dividing off a lower ink compartment 26 in the barrel 10. A tube 27 extends through the bottom 14 of the piston chamber 13 to the lower portion of the 10 compartment 26, said tube being provided with perforations 28 adjacent its top and bottom as shown.

In use and in operation, when it is desired to fill the pen with ink, the point thereof is immersed 15 in the ink in the usual way and the plunger 21 depressed and released several times. The first depression of the plunger 21 will expel air from the barrel 10 so that when the piston 19 is released, ink will be drawn into said barrel. Some 20 of this ink will remain in the lower compartment 26 but a good portion thereof will ascend into the piston chamber 13. Upon the next depression of the piston 19 the ink in the chamber 13 will be expelled therefrom, some of it passing into 25 the compartment 26 and some of it passing outwardly through the pen point 11. Upon the next upward stroke of the piston 19 ink will be again drawn into the compartment 26 and the piston 30 chamber 13 very nearly, if not entirely, filling 30 both. Another stroke of the piston 19 will completely fill both piston chamber 13 and compartment 26. When it is desired to expel the ink for any reason, repeated strokes of the piston 19 will 35 accomplish this. The perforations 15 and 28 facilitate the transference of the ink as above outlined.

By this arrangement it will be noted that a fountain pen is provided having two ink chambers, thus affording a larger ink capacity. The 40 separation of the ink chamber of the pen into two distinct compartments affords great ink capacity and at the same time lessens the weight of the bulk of the chamber in direct communication with the pen point. By making one complete 45 stroke of the piston a downward stroke thereof with the pen point immersed in the ink and then removing the pen point from the ink and releasing the plunger, the lower compartment only will be supplied with ink, thus lessening chances of 50 leakage, or bleeding of the ink.

The use of the metallic lining for the piston chamber insures a tight fitting of the piston 55 therein at all times, thereby insuring efficient operation in filling the pen and also preventing

leakage or bleeding of the ink therefrom in the pocket of the user.

In the modification illustrated in Figs. 3 and 4, the piston chamber 13 is omitted from the head 5 12 and the piston 19' operated in an ink chamber extending the full operative length of the barrel 10 and lined throughout with a metallic sleeve or tube 16'. As will be noted, the effective stroke 10 of the piston 19' is substantially the full effective 15 length of the ink chamber so that one stroke of the plunger will be sufficient to completely fill the ink chamber. The use of the metallic lining for the ink chamber insures a proper fit for the piston at all times, thereby facilitating filling of 15 the pen and also preventing leakage.

While I have illustrated and described the preferred forms of construction for carrying my invention into effect, these are capable of variation and modification without departing from the 20 spirit of the invention. I, therefore, do not wish to be limited to the precise details disclosed, but desire to avail myself of such variations and modifications as fall within the scope of the appended claims.

25 I claim:

1. A fountain pen comprising a barrel having an ink chamber therein; a pen point at one end of said barrel in communication with said chamber; a head closing the other end of said barrel 30 and having an open socket in alignment with said chamber; a piston operating in said chamber and having a piston rod passing through said socket; an enlarged plunger head at the other end of said rod and slidably fitting said socket; and a compression spring imprisoned in said socket. 35

2. A fountain pen comprising a barrel having an ink chamber therein; a pen point at one end of said barrel in communication with said chamber; a head closing the other end of said barrel 40 and having a protruding extension provided with an open socket in alignment with said chamber; a piston operating in said chamber and having a piston rod passing through said socket; an enlarged plunger head at the other end of said rod and slidably fitting said socket; and a compression spring imprisoned in said socket. 45

3. A fountain pen comprising a barrel having an ink chamber therein; a pen point at one end of said barrel in communication with said chamber; a partition dividing said chamber into two compartments; a piston operating in the upper compartment; and a tube extending through said partition to the bottom portion of the lower compartment. 50

55 4. A fountain pen comprising a barrel having an ink chamber therein; a pen point at one end of said barrel in communication with said chamber; a partition dividing said chamber into two compartments; a piston operating in the upper compartment; and a tube extending through said partition to the bottom portion of the lower compartment, there being perforations in said tube adjacent its top and bottom. 60

5. A fountain pen comprising a barrel having 65 an ink chamber therein; a pen point at one end

of said barrel in communication with said chamber; a head closing the other end of said barrel and having a piston chamber extending into said ink chamber and a protruding extension having an open socket in alignment with said piston chamber; a piston operating in said piston chamber and having a piston rod passing through said socket; an enlarged plunger head at the outer end of said rod and slidably fitting said socket; a compression spring imprisoned in said socket; and a tube extending through the bottom of said piston chamber to the bottom portion of the lower compartment. 5

6. A fountain pen comprising a barrel having an ink chamber therein; a pen point at one end of said barrel in communication with said chamber; a head closing the other end of said barrel and having a piston chamber extending into said ink chamber and a protruding extension having an open socket in alignment with said piston chamber; a piston operating in said piston chamber and having a piston rod passing through said socket; an enlarged plunger head at the outer end of said rod and slidably fitting said socket; a compression spring imprisoned in said socket; and a tube extending through the bottom of said piston chamber to the bottom portion of the lower compartment, there being perforations in said tube adjacent its top and bottom. 15 20 25

7. A fountain pen comprising a non-metallic barrel having an ink chamber; a pen point at one end of said barrel in communication with said chamber; a head closing the other end of said barrel and having a piston chamber extending into said ink chamber and a protruding extension having an open socket in alignment with said piston chamber; a metallic lining for said piston chamber; a piston operating in said piston chamber and having a piston rod passing through said socket; an enlarged plunger head at the outer end of said rod and slidably fitting said socket; a compression spring imprisoned in said socket; and a tube extending through the bottom of said piston chamber to the lower barrel compartment. 30 35

8. A fountain pen comprising a non-metallic barrel having an ink chamber; a pen point at one end of said barrel in communication with said chamber; a head closing the other end of said barrel and having a piston chamber extending into said ink chamber and a protruding extension having an open socket in alignment with said piston chamber; a metallic lining for said piston chamber; a piston operating in said piston chamber and having a piston rod passing through said socket; an enlarged plunger head at the outer end of said rod and slidably fitting said socket; a compression spring imprisoned in said socket; and a tube extending through the bottom of said piston chamber to the lower barrel compartment, there being perforations in said tube adjacent its top and bottom and another perforation extending through the bottom of said piston chamber. 40 45 50 55 60 65
